(57) **CLAIM**

The ornamental design for a hygienic contact lens inserter, as shown and described.

DESCRIPTION

FIG. 1 is a perspective view of a hygienic contact lens inserter showing my new design;

FIG. 2 is a perspective view thereof;

FIG. 3 is a front elevational view thereof;

FIG. 4 is a top plan view thereof;

FIG. 5 is a bottom plan view thereof;

FIG. 6 is a perspective view of a hygienic contact lens inserter in an alternate, inverted position;

FIG. 7 is a perspective view thereof;

FIG. 8 is a front elevational view thereof;

FIG. 9 is a top plan view thereof;

FIG. 10 is a bottom plan view thereof;

FIG. 11 is a perspective view of a hygienic contact lens inserter with a cover;

FIG. 12 is a perspective view thereof;

FIG. 13 is a front elevational view thereof;

FIG. 14 is a top plan view thereof; and,

FIG. 15 is a bottom plan view thereof.

The broken line showing of a contact lens is included for the purpose of illustrating environmental structure and forms no part of the claimed design.
